5-617

FIGURE 1 is a right side elevational view of the sliding crane with its boom extended;

FIGURE 2 is a left side elevational view thereof in the direction of arrows 2—2 of FIGURE 5 with the boom extended;

FIGURE 3 is a right side elevational view thereof with the boom retracted;

FIGURE 4 is a partial bottom view thereof in the direction of arrows 4—4 of FIGURE 1;

FIGURE 5 is a front elevational view thereof in the direction of arrows 5—5 of FIGURE 1;

FIGURE 6 is a rear elevational view thereof in the direction of arrows 6—6 of FIGURE 2; and

FIGURE 7 is a perspective view thereof.

The dominant features reside in the solid line portions.

We claim:

The ornamental design for a sliding crane, as shown and described.
